UNITED STATES PATENT OFFICE.

HENRY T. WEAVER, OF HEART LAKE, ALBERTA, CANADA.

VARIABLE-SPEED DRIVE.

1,370,389.

Specification of Letters Patent.

Patented Mar. 1, 1921.

Application filed June 19, 1919. Serial No. 305,243.

To all whom it may concern:

Be it known that I, HENRY T. WEAVER, a subject of the King of Great Britain, residing at Heart Lake, in the Province of Alberta and Dominion of Canada, have invented new and useful Improvements in Variable-Speed Drives, of which the following is a specification.

The purpose of the invention is to provide a new and improved form of drive particularly adapted to fanning mills and the like, whereby the speed of the fanning apparatus may be varied with the speed of the driving mechanism remaining constant. To

this end the invention comprises the combination with a frame, particularly the frame of a fanning mill, of a driving element composed of two beveled gears mounted in common, a beveled gear mounted on the shaft of the fanning blades, and shaft carrying beveled pinions, the one meshing with the gear on the shaft carrying the fanning blades and the remainder meshing alternately with the two gears which are mounted in common, so that either one of the last said pinions may be employed in the transmission of motion from the first said gear to the gear carried on the shaft of the fanning blades.

The invention is illustrated and described in a particular embodiment and is shown as a driving mechanism for a fanning mill, taking the place of the usual chain employed for this purpose. It is obvious, however, that, by a variable speed driving mechanism, it may be employed for other purposes than that in which it is shown and for this reason the right is reserved to make any changes or alterations required to adapt it for particular purposes, in so far as such changes or alterations are compatible in spirit with the annexed claim.

In the accompanying drawings:

Figure 1 is a view in side elevation of a fanning mill frame with the improved variable speed drive attached or mounted thereon.

Fig. 2 is an end elevational view of the structure shown in Fig. 1.

Fig. 3 is a section on the line 3—3 of Fig. 1.

As illustrated, the invention is employed as a means for driving a fanning mill having the usual frame 1 which supports the shaft 2 in the usual manner, this shaft carrying and driving when it is turned the

fanning blades 3. On one end of the shaft 2 and on the outside of the frame 1 there is mounted a beveled gear 4 in mesh with which there is a beveled pinion 5, the latter being carried by the lower end of a diagonally disposed sectional shaft rotatably mounted in appropriate bearings 6 which are supported on the diagonally disposed struts or braces 7. The two-part shaft consists of a tubular section 8 and a solid section 9, the latter telescoping into the former and being locked therein by means of set screws 10 which threadingly engage the tubular section and bear upon the solid section 9. The solid section 9 telescopes the tubular section for a greater part of the length of the latter and this construction obviously permits the elongation of the sectional shaft or the shortening thereof for a purpose hereinafter appearing.

Rotatably supported in appropriate bearings carried by the frame 1 there is a main shaft 11 on which there is carried a double gear element consisting of the gear 12 and 80 the gear 13, the latter being larger than the former and in surrounding relation to it, the two gears rotating about the axis of the shaft 11 as a common center. There is provided for meshing with the gear section 13 a 85 beveled pinion 14 which is carried by the section 9 of the two-part shaft. This pinion is formed with a spline in which a key 15 carried by the shaft 9 engages. On the extremity of the section 9 a beveled pinion 16 90 is carried, this pinion being fixedly attached to the section 9 and movable into a position where it will mesh with the teeth of the gear section 12 or into a position where it will stand between this gear section and the 95 gear section 13.

The elongation of the two-part shaft is effected by loosening the set screws 10 after which the section 9 of the two-part shaft may be raised, this lengthening of the shaft 100 throwing the pinion 16 into mesh with the gear section 12. The pinion 14 being slidably mounted on the section 9, this section will slide through it until the key 15 stands in the same position with respect to the gear 105 section 12 that the pinion 16 previously occupied. The key then will have been disengaged from the pinion 14 with the result that the latter will float on the section 9 and if the double beveled gear composed of 110 the sections 12 and 13 be rotated, the two-part shaft will be driven through the sec-

tion 12 because of its meshing with the pinion 16 and the latter turning the two-part shaft whose rotary motion is communicated to the shaft 2 through the gear couple composed of the pinion 5 and gear 4.

- The shaft 11 on which the double beveled gear is carried is rotated and with it the double beveled gear by means of a crank 17 which is connected with a double beveled gear, the latter being fixedly attached to the shaft 11. Assuming the angular movement of the crank 17 to always be moved at a uniform angular speed, the speed of the shaft 2 and with it the fanning blades 3 will be less with the pinion 16 meshing with the gear section 12 than with this pinion thrown out of mesh with its attendant gear section and the pinion 14 positively connected with the two-part shaft, as it will be when the shaft is shortened by loosening the set screws 10 and moving the section 9 farther into the tubular section 8, when the pinion 16 will be withdrawn from engagement with the gear section 12 and the key 15 made to engage in the key spline formed in the pinion 14. The turning of the crank 17 at the same angle of velocity as before will then result in an angular velocity being had by the fanning blades 3.
- From the foregoing description and the accompanying drawings, it is believed that

a clear enough understanding of the invention is to be had to render further description unnecessary.

The invention having been described what is claimed as new and useful is:

The combination of a driven member, a driving member, a dual beveled gear carried by the driving member and formed with one of its gear elements in surrounding relation to the other but concentric therewith and having its teeth spaced from the teeth of the other said beveled gear, a two-part extensible shaft having one section operatively connected with the driven member, a key carried in the other section of said shaft, a beveled pinion meshing with the larger of the gears of the dual beveled gear and having a spline in which said key may engage, and a beveled pinion positively connected to the extremity of the said other section of the extensible shaft, means whereby the latter may be varied in length to throw the last named beveled pinion into or out of operative connection with the smaller of the gears of the dual gear and engage or disengage the said key with the said spline so that the speed of the driven member may be varied with constant speed of the driving member.

In testimony whereof I affix my signature.
HENRY T. WEAVER.
